Calif., a corporation of California

Application January 23, 1945, Serial No. 574,118

4 Claims. (Cl. 250—27.5)

1

Our invention relates to a multi-unit tube, and more particularly to a twin tetrode.

It is among the objects of our invention to provide an improved tube structure, embodying a plurality of tetrode units in a single envelope, with an arrangement adapting the tube for high frequency operation.

The invention possesses other objects and features of advantage, some of which, with the foregoing, will be set forth in the following description of our invention. It is to be understood that we do not limit ourselves to this disclosure of species of our invention as we may adopt variant embodiments thereof within the scope of the claims.

Referring to the drawing:

Figure 1 is a side elevational view, substantially full scale, of our tube; and

Figure 2 is a horizontal sectional view of the same taken in a plane indicated by line 2—2 of Figure 1.

Figure 3 is a vertical sectional view of the tube taken in a plane indicated by line 3—3 of Figure 2; and

Figure 4 is a similar view taken in a plane indicated by line 4—4 of Figure 2.

In terms of broad inclusion, our improved tube comprises an envelope, a plurality of tubular anodes in the envelope, and a set of electrodes projecting into each anode, each set including a cathode and control grid and screen grid. The conductor means for the anodes extend into one end section of the envelope, and the conductor means for the sets of electrodes project into the other end section; the envelope sections being sealed together in a plane transverse to the anode axes. A pair of spaced metallic condenser members are also preferably provided in the envelope, one member being connected to the cathodes and the other to the screen grids. One of these members is preferably disposed to also function as a shield between the anodes and the lower portions of the envelope.

In greater detail, and referring to the drawing, our preferred tube structure comprises an evacuated envelope of vitreous material, such as glass, made up of upper and lower cup-shaped sections 2 and 3 fused together at annular seal 4 in a plane transverse to the vertical axis of the envelope. These sections or end portions of the en-

2

velope have cylindrical side walls, the top 5 of the upper section and bottom 6 of the lower section being rounded or dome-shaped for strength. Bottom wall 6 carries a centrally disposed exhaust tubulation which is sealed off at tip 7 after the tube is evacuated.

A plurality of tetrode units are arranged in the envelope along parallel vertical axes. In the tube illustrated there are two of these units spaced 10 on opposite sides of the tube axis. Each unit includes a tubular anode 8 of suitable metal, preferably cylindrical in shape. The lower ends of the anodes are open ended and the upper ends are preferably covered with caps 9. For convenience of manufacture cap 9 is preferably formed separately and welded to the rim of the anode, although it may be formed integrally with the body of the anode. Openings 11 in the anode structure adjacent the capped end are provided 20 so that an operator can check alignment of the internal parts.

Conductor means for the anodes is arranged to extend into upper section 2 of the envelope. We prefer to provide a pair of leads 12 coaxial with 25 the anodes and extending through top wall 5 at seals 13 on tubulations 14. The anodes are supported on these leads by suitable brackets 16, preferably of conical shape having their converging ends welded to the leads and their diverging ends welded to caps 9.

A set of electrodes is arranged to project upwardly into each anode, each set including a cathode 17, control grid 18 and screen grid 19. Cathode 17 is preferably of the thoriated type 35 comprising a helical filament having its upper end welded to a center rod 21 and its lower end terminating in a depending tab 22. Control grid 18 interposed between the cathode and screen grids is preferably of the cage type fabricated 40 from wire of suitable metal and terminating in a base ring 23. Screen grid 19 is also preferably of the cage type and terminates in a base ring 24. Ring 23 of the control grid extends below ring 24 to facilitate mounting of the parts. It 45 will be observed that these sets of electrodes are free-ended so that they may be inserted into the open ends of the anodes when the tube is assembled.

Conductor means for the sets of electrodes is 50 arranged to extend into lower section 3 of the

envelope. We prefer to provide a series of seven leads arranged in a circle and extending through bottom wall 6 at seals 26. This series includes a pair of screen grid leads 27, a pair of control grid leads 28, a pair of cathode leads 29 and a common cathode lead 31. The several electrodes in the before mentioned sets are mounted on these leads so that all of the cathodes and grids are supported on lower section 3 of the envelope independent of section 2 which carries the anodes.

As shown in Figures 2 to 4, center rods 21 of the cathodes have outturned ends 32 welded to leads 29. Depending filament tabs 22 are connected together by a strap 33 which in turn is welded at the center to the upturned end of an angle bracket 34, the horizontal leg of this bracket being welded to lead 31. Thus, one end of each filament is electrically connected to a separate lead 29 while the other ends are connected to a common lead 31. Control grids 18 are conductively supported on leads 28 by ears 36 welded to angle brackets 37. Screen grids 19 are conductively supported on leads 27 by ears 38.

In our preferred tube structure a metallic shield 39 is disposed transversely of the envelope below anodes 8. This shield is mounted at the center on the upturned end of bracket 34 by collar 41, thereby supporting it with the sets of electrodes on the lower envelope section and electrically connecting it to the common cathode lead 31. In usual operating circuits the common cathode lead is grounded, so that shield 39 is at ground potential. Apertures 42 in the shield provide openings through which the sets of electrodes project. The shield preferably has a depending annular flange 43, providing an inverted cup-shaped structure to afford maximum shielding between the anode assembly and the conductors which lead to the other electrodes.

A pair of spaced metallic condenser members are also preferably arranged in the envelope to increase the capacitance or bypass between the screen grids and ground. Shield 39 preferably functions as one of these members, it being connected to the common cathode lead through bracket 34 as already described. The second member preferably comprises an annular metallic strip 44 spaced inwardly from annular shield flange 43. These ring-shaped members 43 and 44 are concentrically disposed about the axis of the tube. Ring 44 is conductively supported on leads 27 by brackets 46, which serves to connect the screen grids together as well as to the inner condenser member. If the additional capacitance between the electrodes is not required, member 44 may be eliminated.

The tube is provided with a base comprising an insulating disk 47 fastened to a metallic shell 48 secured to envelope section 3 by cement 49. Central aperture 51 in disk 47 provides clearance for tip 7. A series of seven prongs 52 on the base are aligned with and secured to the cathode and grid leads. This base is of course applied as a final operation, after the envelope is evacuated.

Our improved twin tetrode structure has several advantages. One is that by incorporating two complete tetrode units in a single envelope, the physical size of each unit is proportionately small, permitting the use of closer spacings between the electrodes. Another advantage is that the particular arrangement of conductor means, with the anode leads out the top and the cathode and grid leads out the bottom, keeps all the leads reasonably short, with maximum spacing

between the anode leads and those for the remaining electrodes. These features, among others, adapt the tube for high frequency operation. The use of tetrode units embodying screen grids, together with the shielding means and condenser members, provides a tube particularly adapted for use as an amplifier and without requiring neutralization in such circuits.

From the standpoint of tube structure, it will be appreciated that a tube of the size indicated by the drawing and having the complexity of structure inherent in the twin tetrode combination, involves some real problems in tube assembly. A major difficulty is to achieve and maintain accurate spacing and alignment between the electrodes in each of the units. Our structure is designed to simplify these problems. It has been pointed out that prior to making seal 4 the envelope is in two separate sections. At this stage anodes 8 are mounted in the envelope section 2 and the other electrodes and parts are mounted on section 3. Since the cup-shaped envelope sections are open-ended the various electrodes may be readily assembled and checked for alignment. Subsequently the two sets of electrodes are inserted into the anodes and the envelope sections fused together at seal 4.

We claim:

1. An electron tube comprising an envelope, a transverse metallic shield in the envelope having apertures therein, tubular anodes in the envelope above the shield, conductor means for the anodes projecting into the envelope above the shield, a pair of concentric grids extending upwardly into each anode, the lower end of the outer grid in each pair registering with a shield aperture, a cathode extending upwardly within each pair of grids, conductor means for the inner grids and said cathodes projecting into the envelope below said shield, means connecting the shield to the cathodes, and a condenser member spaced from the shield and connected to the outer grids.

2. An electron tube comprising an envelope, a plurality of anodes in the envelope, a screen grid and control grid and cathode adjacent each anode, a condenser member in the envelope connected to the cathodes, and a second condenser member spaced from the first member and connected to the screen grids, one of said members extending transversely of the envelope providing a shield between end portions thereof.

3. An electron tube comprising an envelope, a tubular anode in the envelope, a screen grid and control grid extending upwardly into the anode, a cathode projecting upwardly into the anode, a condenser member in the envelope connected to the cathode, and a second condenser member spaced from the first member and connected to the screen grid, one of said members extending transversely of the envelope below the anode providing a shield between said anode and the lower end portion of the envelope.

4. An electron tube comprising an envelope, an anode supported on the upper portion of the envelope, a set of electrodes including a screen grid and control grid and cathode adjacent the anode, conductor means for said electrodes on the lower portion of the envelope, a condenser member in the envelope connected to an electrode of said set, and a second condenser member in the envelope spaced from the first member and connected to another electrode of said set, one of said members extending transversely of the envelope.

velope providing a shield between the anode and said lower portion of the envelope.
